(57) CLAIM

I claim the ornamental design for a purse wallet, as shown and described.

DESCRIPTION

FIG. 1 is a front perspective view of my new design for a purse wallet;

FIG. 2 is a front elevation view thereof;

FIG. 3 is a right side view thereof;

FIG. 4 is a left side view thereof;

FIG. 5 is a top view thereof;

FIG. 6 is a bottom view thereof;

FIG. 7 is a back elevation view thereof; and,

FIG. 8 is a perspective front view, showing the purse wallet in an open configuration.

The broken lines representing stitching are part of the claimed design.
